US0D1002425S

(12) **United States Design Patent** (10) **Patent No.:** **US D1,002,425 S**
(45) **Date of Patent:** **** Oct. 24, 2023**

(54) **EARRING**(71) Applicant: **Venus by Maria Tash, Inc.**, New York, NY (US)(72) Inventor: **Maria Tashjian**, New York, NY (US)(73) Assignee: **Venus by Maria Tash, Inc.**, New York, NY (US)(***) Term: **15 Years**(21) Appl. No.: **29/833,404**(22) Filed: **Apr. 4, 2022****Related U.S. Application Data**

(63) Continuation of application No. 29/799,479, filed on Jul. 14, 2021, now Pat. No. Des. 947,708, which is a continuation of application No. 29/796,651, filed on Jun. 25, 2021, now Pat. No. Des. 948,374, which is a continuation of application No. 29/759,055, filed on Nov. 19, 2020, now Pat. No. Des. 934,725, which is a continuation of application No. 29/698,299, filed on Jul. 16, 2019, now Pat. No. Des. 902,771.

Primary Examiner — W. A. Teddy Falloway*Assistant Examiner* — Sarah J Ault(74) *Attorney, Agent, or Firm* — Dentons US LLP(57) **CLAIM**

The ornamental design for an earring, as shown and described.

DESCRIPTION

FIG. 1 is a front perspective view of an earring;
FIG. 2 is a front side view of the earring;
FIG. 3 is a back side view of the earring;
FIG. 4 is a left side view of the earring;
FIG. 5 is a right side view of the earring;
FIG. 6 is a bottom side view of the earring; and,
FIG. 7 is a top side view of the earring.
Broken lines shown in drawings illustrate portions of the earring that form no part of claimed design.
